UNITED STATES PATENT OFFICE.

CARL SCHRADER, OF HALENSEE, NEAR BERLIN, GERMANY, ASSIGNOR TO SIEMENS & HALSKE, A. G., OF BERLIN, GERMANY, A CORPORATION OF GERMANY.

HIGH-TENSION TRANSFORMER.

1,154,132.

Specification of Letters Patent. Patented Sept. 21, 1915.

Application filed December 2, 1910. Serial No. 595,277.

To all whom it may concern:

Be it known that I, CARL SCHRADER, a subject of the German Emperor, and residing at Halensee, near Berlin, Germany, have invented certain new and useful Improvements in High-Tension Transformers, of which the following is a specification.

My invention relates to transformers for current of high tension, and a primary object is to provide such a transformer which substantially consists of only a few turns of the primary conductor, an iron core, carrying the secondary winding, surrounding the primary conductor, and a suitable insulator interposed between the iron core and the conductor. When employing such transformers for very high voltages for example over 30,000 volts, various disadvantages are observed which particularly result from the undue increase in the size of the insulator construction surrounding the primary conductor, both in length and in thickness, in order to prevent the current jumping across from the ends of the primary conductor to the low tension winding surrounding the central portion of the insulator. The detail construction of such insulators *per se* is known in the art. Also due to such increase in insulator size the magnetic connection between the primary and secondary windings is insufficient owing to the great distance of the iron body from the former winding, this being more apparent in such transformers because of the very small strength of current traversing the primary conductor at such high voltages. Such devices satisfy only very small demands with regard to both the constancy of the ratio of transformation and also to defects due to displacement of phase between the primary and secondary currents, and consequently are quite unsuitable for purposes requiring great exactitude, for example for connecting to wattmeters of various kinds. Now according to my invention I remedy these defects in an exceedingly simple manner by employing an insulator which has heretofore been employed for connectors. This insulator comprises a plurality of concentric insulating cylinders which are each shorter than the next inner one and are separated by layers of metal. These conducting layers cause the distribution of voltage on the free surface, and that within the dielectric to suit one another. By suitably selecting the distance between the

individual conducting layers and correspondingly shaping the non-covered dielectric, a definite fall of voltage can be caused between the surface parts of the dielectric, and the non-uniform distribution of voltage on the surface of insulators, which exists in the case of ordinary insulators and, as is known, causes the current to jump across, is avoided. Owing to employing such an insulator, which by virtue of its peculiar action can be made materially smaller, both in length and in diameter, than the insulators otherwise customary in such transformers, my transformer is not only materially smaller and cheaper than the well-known forms of such transformers, but it possesses, above all, materially better electrical properties, as it is possible to place the iron core carrying the secondary winding in immediate proximity to the primary conductor surrounded by it.

Several illustrative embodiments of my invention are represented by way of example in the accompanying drawing, where-in:—

Figures 1 and 2 are elevation and top plan view, respectively, showing a form comprising a primary winding composed of several strands connected in series and passing through two insulators, and Figs. 3 and 4 are like views, respectively, showing a form in which the secondary winding is arranged on both the insulators.

In these illustrative embodiments of my invention the primary conductor comprises a number of wires a_1, a_2, a_3 insulated from one another, connected in series and arranged in two parallel insulating sleeves each comprising a plurality of concentric insulating cylinders b , which are preferably graduated outwardly in length and are separated from each other by layers of metal c . The laminated annular iron core d on which the secondary winding e is placed surrounds the central portion of the sleeve. In the illustration shown in Figs. 1 and 2 only one of the sleeves is provided with iron core carrying the secondary winding e .

In the illustrative embodiment shown in Figs. 3 and 4, the current passing through the second sleeve is also utilized for producing secondary current. To this end, a second iron core having a secondary winding e_1 is provided on the second insulating sleeve. The two secondary windings e and e_1 are

connected in series. In such an arrangement and with an equally large output, the number of the requisite primary turns can be reduced to one-half as compared with the arrangement according to Figs. 1 and 2, or when the number of turns is the same, the output of the transformer can be doubled, so that such an arrangement is the most perfect one with regard to the electrical utilization of the individual parts.

10 The double transformer may be secured in position in any desired manner, for example by means of the brackets *k* which are attached to clamps *k* surrounding the insulator close to the secondary winding.

15 It will thus be seen that the construction according to my invention possesses various advantages as compared with the constructions heretofore devised. In my present high tension transformer, whose low tension winding carries the current to the measuring instrument, the primary winding carries the entire high tension current which is to be measured. Also in every case I employ a construction representing a single transformer, thereby avoiding the disadvantage following from the employment of two transformers, the direct transformation of the high tension current in a single transformer forming part of my present invention. By this I do away with the double transformation of the current to be measured.

I claim:—

35 1. In a transformer of the character described, the combination with a primary winding, comprising a coil having a suitable number of turns, two insulating sleeves disposed on said coil substantially parallel and adjacent to each other, magnetic material surrounding the insulated portion of the said primary winding and a secondary winding disposed on said magnetic material.

40 2. In a transformer of the character described, the combination with a primary winding comprising a coil having a suitable number of turns, two insulating sleeves each surrounding said coil and placed substantially parallel and adjacent to each other, an iron core surrounding one of said sleeves midway between its ends and a secondary winding mounted on said iron core.

45 3. In a transformer of the character described, the combination with a primary winding consisting of a plurality of turns, an insulating sleeve comprising a number of alternately arranged concentric cylinders of insulating material and metal, a second insulating sleeve built up similarly to said first named sleeve, said sleeves surrounding said

5 turns of said primary winding and being placed substantially in parallel and adjacent to each other, an iron core surrounding one of said sleeves midway between its ends, a secondary winding mounted on said iron core, whereby the other sleeve insulates the portion of said primary winding located outside of said core from said secondary winding and core.

4. In a transformer of the character described, the combination with a primary winding consisting of a coil having a suitable number of turns, an insulating sleeve comprising a number of alternately arranged concentric cylinders of insulating material and metal, a second insulating sleeve built up similarly to said first mentioned sleeve, said two insulating sleeves being disposed on said coil substantially in parallel and adjacent to each other, an iron core surrounding one of said sleeves midway between its ends, a secondary winding mounted on said iron core, whereby an insulation is secured between the portion of said primary winding located outside of said core and said secondary winding and core.

5. In a transformer of the character described, the combination with a primary winding consisting of a coil of a suitable number of turns, an insulating sleeve surrounding said turns of said coil, a second insulating sleeve also surrounding said coil, said sleeves being placed adjacent to each other and substantially in parallel, an iron core disposed on each of said sleeves midway between its ends and a secondary winding mounted on each of said iron cores and being connected in series with each other.

6. In a transformer of the character described, the combination with a primary winding consisting of a coil having a suitable number of turns, an insulating sleeve comprising a plurality of alternately arranged concentric cylinders of insulating material and metal, a second insulating sleeve built up similarly to said first mentioned sleeve and being placed in parallel and adjacent to said former sleeve an iron core disposed on each of said sleeves midway between the ends thereof, the secondary windings on said cores being connected in series.

In testimony whereof I have signed my name to this specification in the presence of two witnesses.

CARL SOHRADER.
